UNITED STATES PATENT OFFICE.

HARRY M. PFLAGER, OF ST. LOUIS, MISSOURI, ASSIGNOR TO COMMONWEALTH STEEL COMPANY, OF ST. LOUIS, MISSOURI, A CORPORATION OF NEW JERSEY.

LOCOMOTIVE BED.

Application filed November 27, 1925. Serial No. 71,640.

My invention relates to railway locomotive structures, and consists in an improved bed for locomotives comprising essentially a box girder throughout the main portion 5 of its length and preferably being formed of a one-piece casting.

The main object of my invention is to produce a locomotive frame possessing, without undue weight, a high degree of rigidity and strength to resist deflection, not only in ordinary service but also when being handled, either alone or when the locomotive assembly is completed, by cranes or otherwise.

15 A further object of my invention is to provide in such a bed integral pedestals also box-shaped in cross section and preferably utilizing the walls of the bed proper as portions of the pedestal walls.

20 Further objects of my invention are to provide in a one-piece casting a bed of the type described having integral cylinders and steam supply chambers, valve gear brackets, brake hanger fulcrums, deck plates, and 25 equalizer brackets, a cradle and a radial pivot bearing.

In the accompanying drawings which illustrate a selected embodiment of my invention:-

30 Figure 1 is a top view of my improved bed.

Figure 2 is a vertical longitudinal section through the center of the bed.

35 Figure 3 is a horizontal longitudinal section taken substantially on line 3-3 of Figure 2.

Figure 4 is a side elevation.

40 Figures 5 to 9 and 12 are vertical transverse sections taken on lines 5-5, 6-6, 7-7, 8-8, 9-9 and 12-12, respectively, of Figure 1.

Figure 10 is a similar section taken on line 10-10 of Figure 4.

45 Figure 11 is a vertical transverse section taken on line 11-11 of Figure 2.

In Figures 2 and 4, the driver, trailer, and pony truck wheels are indicated in broken lines.

50 As more clearly indicated in the cross sectional views, the body of the bed is box-shape in cross-section and includes sides 1, and top and bottom walls 2 and 3, respec-

tively, these walls being provided with suitable openings 4 at intervals which lighten the structure without weakening it for the 55 purpose indicated. Similarly the side walls 1 are provided with openings 5. At intervals along the bed are walls 6 paralleling side walls 1 and cooperating therewith to form pedestal jaws for receiving the driver 60 boxes. The pedestal jaws so formed are also box-shape in cross section and the form of the bed and pedestals is such that flanges are omitted on the outside of the bed, thereby avoiding interference with the application and removal of the springs and equalizers; in other words, affording maximum clearance between the wheels and bed casting. I have indicated the sides of the main frame as being indented at 1^a to provide further clearance between the same and the 65 drivers and their boxes.

At the rear of the bed proper I form the cradle consisting of side frames 7, a rear deck 8, and lateral extensions 9 provided 75 with side bearings for resting upon the trailer truck (not shown). Preferably, the cradle is formed integrally with the body of the bed, the side frames 7 merging with and forming a continuation of walls 6 of the 80 rear driver box pedestal. The rear end of the cradle has an integral drawbar pocket 10.

The rear end of the body of the bed has a pivot bearing 11, formed integrally on its 85 lower wall 3, to which the forward portion of the trailer truck frame (not shown) may be secured in the usual manner.

Formed integrally with the pedestal jaws are fulcrums 12 for the attachment of brake 90 hangers and also formed integrally with the pedestals are equalizer fulcrums 13. Brackets for the valve gear are indicated at 14, these being formed integrally with the bed and projecting outwardly therefrom. 95 The forward portion of the frame is formed integrally with the main body portion but is reduced in height and preferably carries integral cylinder 15 and steam supply chambers 16 similar to the disclosure in my co-pending application Serial No. 752,277, filed Dec. 11, 1924, and patented Dec. 22, 1925, No. 1,566,423. 100

If it is desired to apply steam cylinders

and supply chests to the bed as separate units, each side wall of the frame may be finished with a finished pad 17, indicated at the righthand side of Figures 1 and 6, to which the cylinders and steam supply devices may be applied in the usual manner.

Intermediate the side walls 1 of the bed are vertical transverse walls 18 which reinforce the structure and these walls may 10 be lightened by suitable openings 19 as shown.

With the above described structure, the individual features referred to are formed as part of a one-piece casting. This eliminates all work and material required for assembling a number of parts and avoids any need for future repairs due to loosening of attached parts. Distances between spaced elements are rigidly maintained. The 20 strength of the frame from end to end is increased and the frame may be handled safely by cranes, jacks, or otherwise, which has not been true herebefore of frames of such size and frequent breakages have occurred prior to the production of the box girder frame illustrated.

I contemplate such modifications of my invention as may be suggested in its commercial development and as are included in 30 the scope of the appended claims.

I claim:—

1. A locomotive bed comprising a one-piece casting forming a box girder.
2. A one-piece casting comprising a locomotive bed box-shape in cross section, and a cradle formed integrally therewith.
3. In a locomotive bed, a main frame consisting of a box girder, and driver box pedestals on the exterior of said girder.
4. In a locomotive bed, a main frame consisting of a box girder, and driver box pedestals on the exterior of said girder and formed integrally therewith.
5. In a locomotive bed, a box girder forming a main frame, and walls paralleling the outer faces of said girder and forming therewith box-shaped pedestals for the driver boxes.
6. In a locomotive bed, a one-piece casting comprising a main frame box-shape in cross section, and driver box pedestals on each side of said main frame, each of which pedestals is box-shape in cross section.
7. In a locomotive bed, a main frame consisting of a box-girder and a cradle extending rearwardly of said main frame and including side frames each integrally connected to the side of said box girder.
8. In a locomotive bed, a main frame consisting of a box girder, supplemental pedestal elements paralleling and formed integrally with the sides of said girder and located outside thereof, and a cradle including side frames integral with said girder and elements and aligned with said elements.
9. In a locomotive bed, a main frame comprising a box girder, integral pedestals positioned outside of said girder, and integral reinforcements extending across said girder adjacent said pedestals. 70
10. In a locomotive bed, a main frame comprising a box girder, and a pivot bearing for a radial trailer truck formed integrally with the bottom of said girder.
11. In a locomotive bed, a main frame 75 comprising a box girder, pedestals outside of said girder and formed integrally therewith, and equalizer fulcrums on the outside of said pedestals and formed integrally therewith.
12. In a locomotive bed, a main frame 80 comprising a box girder, vertical walls spaced from the sides of said girder, and integral projections on said walls and girder sides forming brake hanger fulcrums.
13. In a locomotive bed, a box girder main frame, integral pedestal jaws formed thereon and projecting outwardly from the main frame, the sides of said main frame being indented between each pair of pedestal jaws. 85
14. In a locomotive bed, a main frame 90 comprising a box girder, pedestals outside of said girder and formed integrally therewith, and valve gear brackets on the outside of said pedestals and formed integrally therewith. 95
15. In a locomotive bed, a main frame comprising a box girder, pedestals, valve gear brackets, brake hanger fulcrums, and a cradle all formed integrally with said girder. 100
16. In a locomotive bed, a main frame comprising a box girder, pedestals, valve gear brackets, brake hanger fulcrums, and cradle side frames all formed integrally with said girder but located outside thereof. 105
17. In a locomotive bed, a main frame comprising a box girder with steam cylinders formed integrally therewith.
18. In a locomotive bed, a main frame 110 comprising a box girder with steam cylinders and valve gear brackets formed integrally therewith.
19. In a locomotive bed, a main frame comprising a box girder with steam cylinders and pedestals formed integrally on the 115 outer faces of said girder.
20. In a locomotive bed, a main frame comprising a box girder with steam cylinders, valve gear brackets and pedestals formed integrally on the outer faces of said 120 girder.
21. In a locomotive bed, a main frame comprising a box girder with steam supply chambers formed integrally therewith.
22. In a locomotive bed, a main frame 125 comprising a box girder with steam cylinders and steam supply chambers formed integrally therewith.
23. In a locomotive bed, a main frame comprising a box girder with steam cylin- 130

ders, valve gear brackets and steam supply chambers formed integrally therewith.

24. In a locomotive bed, a main frame comprising a box girder with steam cylinders, valve gear brackets, steam supply chambers, and pedestals formed integrally therewith.

25. In a locomotive frame, a main frame comprising a box girder with steam cylinders, steam supply chambers, pedestals, and 10 a cradle frame, all formed integrally.

In testimony whereof I hereunto affix my signature this 17th day of November, 1925.

H. M. PFLAGER.
